J. C. Barnes,

Inventor
John F. Steward.

UNITED STATES PATENT OFFICE.

JOHN F. STEWARD, OF CHICAGO, ILLINOIS.

GRAIN-DIVIDER FOR HARVESTERS.

SPECIFICATION forming part of Letters Patent No. 708,497, dated July 1, 1902.

Application filed April 21, 1902. Serial No. 104,039. (No model.)

To all whom it may concern:

Be it known that I, JOHN F. STEWARD, of Chicago, in the county of Cook and State of Illinois, have invented certain new and useful Improvements in Grain-Dividers for Harvesters, of which the following is a full description, reference being had to the accompanying drawings, in which—

Figure 1 is a grain-side elevation showing my invention; Fig. 2, a top view of the same, less the divider-board; and Fig. 3, a grain-side view of the divider when folded.

My invention relates to grain-dividers of the kind adapted to be folded rearwardly, so that the projecting forward end shall not extend beyond other portions of the machine, and thus the latter be narrowed, so that it may be drawn endwise through gates and also occupy less space in storage.

My divider is applicable to any style of grain-harvesting machine. The platform may consist of the rear sill B, the finger-bar C, the bottom A, and the bar E, the latter secured in any suitable manner to the other parts which constitute the grain end of a harvesting-machine. In this instance I secure a casting D to the finger-bar, having the lugs d and d', to which I hinge the forward extension of the divider. For convenience I secure the forward end of the bar E to this casting. The grain-receiving platform, however, may be of any desired construction.

The present invention may be considered an improvement on the one forming the subject-matter of the patent granted to me March 4, 1902, and numbered 694,441. In the present instance I secure a post H to the grain end of the platform, preferably to the bar E of the grain-receiving platform structure.

F is the forward extension of the divider, suitably braced by the bar F'. If material of ample strength be selected, the single bar F will be sufficient, however.

I is the divider-board, doubly inclined, as is usual in harvesting-machines, rigidly secured at its forward end to the divider-point G. The forward extension is pivoted by the bolt g to the said divider-point. As an easy means of securing the divider-board to the post H, I bend the latter at its upper end to

conform to the inclination of the said board, as shown in Fig. 1, and secure it there by suitable locking or latching means. From preference, however, I use simply the bolt i, having a thumb-nut i'. In the post H, I provide the hole h. In the bar F, I also provide a hole f. The hole f and that h are so located in the respective parts that when the extension is folded to the position shown in Fig. 1 the bolt i' may serve as simple means for locking the two parts together. A special bolt may be placed through the holes f and h, thus supplying the post H with two locking devices; but I prefer to use the single bolt, as it alone serves the purpose of two locking devices.

In order to guide the grain to the stubble-side of the point of the outermost divider, the shield a' may be used. In the board I, I provide a series of holes i². By placing the bolt i in the foremost one of these holes the divider-point is held higher from the ground than if placed in any other of the holes, which is a desirable feature. The divider-point is, in effect, but a shoeing for the forward end of the grain-divider board and may be considered as one piece with the board. So viewed it will be readily understood that the board is, in effect, pivoted to the forward end of the forward extension. If the brace F' is used, then the space between it and the bar F must be sufficient to let the two parts pass behind the bent top of the post H, unless the post be placed so far forward that the parts will not need to pass to the full backward position. (Shown in Fig. 3.)

What I claim as my invention, and desire to secure by Letters Patent, is—

In combination with a grain-receiving platform, the forward extension pivoted at its rear end to said platform, the divider-board I pivoted to the forward end of said forward extension, the post H, means for securing the board to the said post, and means for securing the forward extension to the said post, substantially as described.

JOHN F. STEWARD.

In presence of—

J. C. WARNEs,
EDWARD BARRETT.
